UNITED STATES PATENT OFFICE.

ROBERT W. DODGE, OF KANSAS CITY, MISSOURI.

HEATING STOVE OR FURNACE.

SPECIFICATION forming part of Letters Patent No. 757,602, dated April 19, 1904.

Application filed June 23, 1903. Serial No. 162,813. (No model.)

To all whom it may concern:

Be it known that I, ROBERT W. DODGE, a citizen of the United States, residing at Kansas City, in the county of Jackson and State of Missouri, have invented a new and useful Heating Stove or Furnace, of which the following is a specification.

This invention relates to heating stoves or furnaces, and has for its object to simplify and improve the construction of such devices and effect a reduction in the consumption of fuel and an increase in the heat generated; and the invention consists in certain novel features of construction, as hereinafter shown and described, and specified in the claims following.

In the drawings illustrative of the invention, in which corresponding parts are denoted by like designating characters, Figure 1 is a vertical sectional side elevation of the device when employed as a heating-stove. Fig. 2 is a plan view with the dome removed. Fig. 3 is a transverse section on the line 3-3 of Fig. 1. Fig. 4 is a plan view of the grate detached. Fig. 5 is a side elevation of the stove in the reverse position to that shown in Fig. 1 with inclosing jacket or shell in vertical section as employed when device is used as a furnace. Fig. 6 is a transverse section on the line 5-5 of Fig. 1. Fig. 7 is a sectional detail of the lower portion of the lower shell-section, illustrating more fully the mechanism for rotating the fire receptacle and grate.

The improvement herein disclosed may be applied to any size of heating stove or furnace, and for the purpose of illustration it is shown applied to a heating-stove of ordinary proportions having an inclosing lower shell-section 10, provided with the fire-receptacle 11 and with a grate 12 and ash-pit 13 in the usual relative locations. The lower section 10 will preferably be of cast-iron and will be surrounded with an upper shell-section 14, preferably of sheet-steel and supported, as at 15, upon the lower section and from which the smoke-flue 16 leads, as shown. Additional smoke-exits 17 may be provided to provide for the discharge at different points or for a plurality of discharge-flues, if required. The upper edge of the lower section 10 is formed with an inwardly-extending annular flange

18, in which spaced sockets are arranged to receive bearing-balls 19, upon which an outwardly-extending flange 20 on the upper edge of the fire-receptacle 11 rests, so that the fire-receptacle may be rotated as required and with the minimum of friction.

The annular flange 21, between the ash-pit 13 and the space surrounding the fire-chamber, is provided with spaced sockets to receive bearing-balls 22, upon which the outer edge of the grate 12 rests to provide for the easy and free rotation of the grate.

The grate 12 is provided with an annular gear-rack 23, and the fire-chamber 11 is likewise provided with a corresponding annular gear-rack 24 in vertical alinement above and spaced from the rack 23, so that one gear-wheel 25, suitably mounted for rotation upon a shaft 26 within the shell 10, will engage both racks, as indicated in Figs. 1 and 7.

The grate 12 will be formed with a central aperture 55, beneath which a grate-section 50 is slidably supported by ways or guides 51, so that a relatively large opening may be formed in the grate to provide means for the removal of the larger clinkers and to assist in controlling the burning fuel.

The gear-wheel 25 will be supported in suitable standards 27 and provided exteriorly of the casing with means 28 for the attachment of an operating handle or wrench, and when thus arranged it will be obvious that the rotation of the handle will cause the corresponding rotation of the fire-chamber and grate in opposite directions.

Between the annular gear 24 and the outer wall of the fire-chamber an annular track 29 is formed, the track providing a surface upon which cams 31 act when rotated to bodily elevate the fire-chamber and provide means for the removal of clinkers, ashes, and other foreign matter and obstructions. To this end a large door 32 is provided in the section 10, as shown, through which the parts may be reached and the clinkers removed when the fire-chamber is elevated.

The door 32 will be provided with draft-slides 33 opposite the ash-pit, as shown in Figs. 1 and 7.

The elevating-cams 31 will preferably be located at equidistant points upon opposite

sides of the shell and far enough from the gear 25 to avoid interference therewith and will be supplied with sockets to receive operating-cranks, as shown.

5 The upper shell 14 is surmounted by an annular top member 34, centrally from which a fuel-magazine 35 is suspended and provided with a detachable cover 36. The lower end of the magazine is preferably contracted slightly 10 and terminates above the center of the fire-receptacle 11 in the usual manner.

Between the shell 14 and magazine 35 is disposed an annular hot-air drum 37, leaving annular air-spaces 38 39, respectively, between 15 the shell and drum and between the drum and magazine, as shown.

The top member 34 is provided with a plurality of spaced apertures 40, and covering these apertures is an annular damper-plate 41, 20 having apertures 42, adapted to register with the apertures 40 in the cover member when the annular plate is rotated in one direction and cut off the apertures when rotated in the opposite direction, the plate thus forming a 25 cut-off or damper to regulate the flow of the air from the drum. The plate 41 may be operated by any suitable means, such as by a handle 43, extending from one side, as shown.

Leading inwardly through the upper section 3c 14 are tapered air-feed pipes 49 50, disposed at opposite sides and with their contracted inner ends or nozzles 51 52 turned downwardly and discharging in opposite directions above the fire in the fire-receptacle, 35 as shown in Figs. 1 and 3. By this simple means a supply of fresh air will be introduced in the form of jets moving in opposite directions above the center of the fire in the fire-chamber, and thus supplying fresh oxygen 40 where most required and greatly accelerate the combustion and completing the consumption of any particles of combustible matter which may escape the fire in the body of the fire-chamber.

45 The pipes 49 50, passing above the fire in the fire-chamber, are highly heated thereby, and consequently highly heat the air passing through them and discharge it in a very highly-heated state and in the best possible 50 condition to produce the requisite supplemental and accelerated combustion.

The tapered pipes 49 50 are very important features of the invention and add materially to the value and effectiveness of the operation.

55 The outer or intake ends of the feed-pipes 49 50 will preferably be provided with closing dampers or slides 53 54 to regulate the flow therethrough.

Near its upper end the magazine 35 will be 60 provided with a plurality of apertures 56 to provide vents for the escape of gas arising from the fuel in the magazine, which thus enters the air-space 39 and is drawn from thence downward into the fire and there consumed 65 and prevented from escaping into the room.

This is a very important feature of the invention and overcomes a very serious objection to many forms of magazine-stoves, as in many of these stoves gas accumulates in the magazines, especially if the fuel runs low, and escapes into the room. With the arrangement herein disclosed, however, all such accumulations of gas are readily disposed of and consumed and are thus not only prevented from 70 escaping into the room, but add to the heat- 75 imparting qualities of the stove.

Leading into the closed lower end of the drum 37 are cold-air ducts 44 45, the ducts extending downward through the flanges 18 and 21 and the bottom of the ash-pit and opening 80 near the floor beneath the stove, as shown. As many of these air-ducts may be employed as required; but generally two will be sufficient, as shown, to secure the necessary uniform distribution.

Above the shell 14 is a "dome" or top 46, from which the final discharge-flue 47 leads, as shown, and supported above this flue is a fan-wheel 48 in position to be rapidly rotated by the rising currents of air and distribute 85 them uniformly in all directions.

The fan-wheel 48 will be increased or decreased in size with the increase or decrease in the size of the stove or furnace and may be formed with as many "wings" or blades as required. The fan-wheel will also serve as an indicator of the action of stove or furnace, disclosing by its speed the volume of the hot air rising through the discharge 47, as the greater the heat the greater will be the volume of air 90 passing through.

The discharge-flue 47 may be conducted to any required distance and in any required direction and may be conducted to other rooms, if required, to supply the heated air to any 105 number of rooms; but wherever and to whatever distance the flue may be conducted the fan member will be placed opposite the final outlet. By this arrangement it will be obvious that the heat rising from the air-drum 110 37 will highly heat the air therein and cause it to escape through the apertures 40 42 and through the dome 46 and discharge-flue 47 to rotate the current-indicating fan-wheel 48, and this upward discharge of hot air will induce 115 an upward flow of the cooler air from near the floor into the drum, and so on continuously, thoroughly and uniformly distributing the heated air and producing a uniform and equable temperature throughout the room 120 or rooms of the building.

When it is desired to shake the grate, a few rapid revolutions of the crank 28 will thoroughly accomplish this result by rotating both the grate and fire-receptacle or "basket" in 125 respectively opposite directions, which will produce a doubly efficacious result, thereby thoroughly and rapidly precipitating the ashes and clinkers and other unconsumed matter. If clinkers accumulate, they can be readily 130

removed, as above noted, by rotating the cams 31, and thereby elevating the basket, leaving a gap between its lower edge and the grate through which the clinkers and other accumulations may be readily removed.

The nozzle-pipes 49 50 are an important adjunct to the device, as they supply the fresh oxygen at the exact point required to produce the best results and effect a complete combustion of the unconsumed particles of carbon and effectually prevent the formation of smoke or the escape of combustible gases, so that nothing but a small amount of incombustible gases escape by the flues 16 or 17. The outer portions may be of any fanciful shape or design and ornamented in any desired manner, parts being nickel-plated or otherwise ornamented or protected.

When employed as a furnace, an outer shell 20 or hood 55 will be employed, as in Fig. 4, and when this is done the dome will be dispensed with, as shown; but otherwise there will be no change in the stove. By this means the stove may be set up in the basement or furnace-room and the usual conductor-flues connected therewith, the large volume of heat being ample to supply the flues, as will be obvious. The shell 55 will be provided with doors corresponding to and located opposite 25 the doors and other openings in the stove, so that the presence of the hood or shell does not interfere with the ordinary operations of the stove, and the operating-handles 28 will likewise pass outwardly through the outer shell.

30 The stoves may be manufactured in any size or of any suitable material and may be employed in all localities where other makes of stoves or furnaces are adapted to be employed.

If required, a vent-opening covered by a 40 movable closure 56 may be arranged in the section 14 of the casing. By this simple arrangement it will be noted the fire-receptacle and grate can be very easily and quickly removed for renewal or repairs or another form 45 of grate or fire-receptacle may be substituted for the one in the shell when the quality or kind of fuel is to be changed. Thus the stove may be quickly and easily changed to adapt it to hard or soft coal or to coarse or fine coal, 50 as required. Thus by furnishing duplicate grates of different "mesh" the same stove may be employed for all the different kinds and sizes of fuel. This is an important advantage and adds materially to the value and 55 efficiency of the device.

The lower shell-section 10, together with the grate, fire-receptacle, and the "noze" or lower discharge end of the magazine, will 60 preferably be of cast-iron, while the upper shell-section, dome, and upper portion of the magazine will preferably be of sheet-steel of sufficient "gage" to withstand the heat and other strains to which it will be subjected.

The device can thus be very durably constructed and all the parts disposed to uniformly

resist the strains to which they will be subjected.

The dome 46 will preferably be arranged to swing laterally, as by a pin 52, to expose the damper 41 and fuel-inlet 36, as shown. 70

Having thus described my invention, what I claim is—

1. In a heating-stove, an outer shell, a fire-receptacle within said shell, and reversely-disposed tapering air-feed pipes leading through 75 said shell and curving downwardly and terminating above the fire in the receptacle, and discharging in opposite directions, substantially as described.

2. In a heating-stove, an outer shell, a fire-receptacle within said shell, reversely-disposed tapering air-feed pipes leading through said shell and curving downwardly and terminating above the fire in the receptacle, and discharging in opposite directions, and control- 85 ling-valves at the inlet ends of said air-pipes, substantially as described.

3. In a heating stove or furnace, a lower shell-section having a fire-receptacle detachably supported therein, a grate movably sup- 90 ported below the fire-chamber, an upper shell-section detachably supported upon the lower shell-section, and reversely-disposed tapering air-feed pipes leading through said upper shell-section and curving downwardly and terminating above the fire and discharging in opposite directions, substantially as described. 95

4. In a heating stove or furnace, a lower shell-section having a fire-receptacle detachably supported therein, a grate movably sup- 100 ported below the fire-chamber an upper shell-section detachably supported upon the lower shell-section, reversely-disposed tapering air-feed pipes leading through said upper shell-section and curving downwardly and terminat- 105 ing above the fire and discharging in opposite directions, and controlling-valves at the inlet-ends of said air-feed pipes, substantially as described.

5. In a heating-stove, an inclosing shell, a 110 fire-chamber and grate in the lower part of said shell, an annular drum supported in said shell and spaced therefrom above said fire-chamber, cold-air flues leading to said drum, means for discharging the heated air from said 115 drum, reversely-disposed tapering air-feed pipes leading through said shell and curving downwardly and terminating above the fire-chamber, and a fuel - magazine within said drum and spaced therefrom and provided with 120 gas-escape apertures connecting with the space between said drum and magazine, substantially as described.

In testimony that I claim the foregoing as my own I have hereto affixed my signature in 125 the presence of two witnesses.

ROBERT W. DODGE.
